CLAIM

The ornamental design for a trailer borne air-inflated safety cushion, as shown and described.

DESCRIPTION

FIG. 1 is a perspective view of a trailer borne air-inflated safety cushion showing my new design, with the safety cushion in collapsed and folded condition. The opposite side elevational view being a mirror image of that shown;

FIG. 2 is a perspective view of a trailer borne air-inflated safety cushion, with the safety cushion in air inflated condition;

FIG. 3 is a top plan view of the air-inflated safety cushion, it being understood that the safety cushion is shown separately for convenience of illustration;

FIG. 4 is a front elevational view of FIG. 3, the rear elevational view being a mirror image of that shown. The bottom of the safety cushion is flat and unornamented.

FIG. 1

FIG. 2

FIG. 3

FIG. 4
